[57] **CLAIM**

The ornamental design for a lamp fixture, as shown and
described.

DESCRIPTION

FIG. 1 is a front elevational view of a lamp fixture
showing my new design.

FIG. 2 is a top plan view thereof.

FIG. 3 is a bottom plan view thereof, the leaves omitted
to clearly show the bottom surface of the globe.

FIG. 4 is a side elevational view thereof taken so as to
clearly show the contours of the leaves.

FIG. 1

FIG. 2

FIG. 3

FIG. 4
